his Attorney

UNITED STATES PATENT OFFICE.

SAMUEL W. RUSHMORE, OF PLAINFIELD, NEW JERSEY.

RADIATOR CONDENSER.

Application filed November 18, 1922. Serial No. 601,682.

To all whom it may concern:

Be it known that I, SAMUEL W. RUSHMORE, a citizen of the United States, and resident of Plainfield, in the county of Union and State of New Jersey, have invented certain new and useful Improvements in Radiator Condensers, of which the following is a specification.

My present invention relates to radiators, particularly radiators for the motor cooling systems of automobiles, trucks and the like particularly when operated as up-flow condensers according to the principles set forth in my prior Patent No. 1,378,724, granted May 17, 1921. In this patent, the cooling water from the motor jacket is short-circuited through the bottom of the radiator and, being insufficiently cooled, gets boiling hot. The space in the bottom of the radiator acts as a separating chamber from which the steam rises into the air-cooled passages of the radiator. The condensate returns by gravity, while the boiling water including condensate is returned to the water jacket by the pump.

In applying this system to automobiles and trucks of standard construction, the large size of the water jacket outlet and its location near the level of the top of the radiator make it awkward to make the down-take a single pipe of the required size, running from the top of the engine down to the bottom of the radiator. Moreover, the discharge of the steaming water into the bottom of the radiator in a single large stream and from one side only, tends to unduly localize the steam evolution under certain parts of the honeycomb.

In these radiators the chamber below the honeycomb is of limited capacity and in certain cases, particularly radiators of the vertical tube type, particularly when used on trucks where the cooling capacity of the radiating tubes is apt to be overtaxed as by running up long grades on low gear, I find that the increase in the volumes of steam from the water discharged into the lower chamber of the radiator is liable to cause the water to be projected at such high velocity as may be driven up through the tubes by momentum.

To meet these and other difficulties of the situation, my present invention includes dividing the stream from the water jacket and providing two outlet pipes, discharging into the lower separating chamber at two

points, preferably in opposite directions and from the respective ends thereof. The branch pipes preferably pass downward adjacent to the rear face of the radiator and 60 they may be anchored thereto if desired.

Preferably the single large pipe outlet from the top of the engine jacket is carried forward to the desired point, preferably the vertical plane of the rear face of the radiator, and from there the branch pipes run down each side. For convenience I may provide a casting somewhat like the usual upper inlet casting at the top of the radiator, but blanked off at the top of the radiator wall so 70 that it serves as a structural anchorage both for the jacket outlet pipe and for its branches.

The branches preferably follow the rear surface of the radiator at or near the margin of the honeycomb. Entering the bottom of the radiator from each side, they preferably discharge toward each other beneath a perforated baffle plate which serves the purpose of distributing the steam more 80 evenly across the bottom of the honeycomb and also operates as a splash plate to minimize slopping of the water into the honeycomb.

The above and other features of my invention may be more fully understood from the following description in connection with the accompanying drawings, in which—

Fig. 1 is a rear elevation of a radiator showing one embodiment of my invention. 90

Fig. 2 is a detail section on the line 2—2, Fig. 1, showing a desirable form of fitting from which the two jacket outlet pipes are branched, and

Fig. 3 is a detail section on the line 3—3, 95 Fig. 1.

The radiator casing 1 and the core or honeycomb 2 may be of any known or desired construction, as for instance, any of those shown in my applications, Serial Numbers 500,581; 500,582; 520,209; or 520,210.

Preferably, however, the casing comprises a bottom chamber or tank 3, a top chamber or tank 4 and the usual filler opening 5 closed by cap 6. For simplicity of illustration, the 105 core is shown as comprising vertical pipes 7, 7, with the usual horizontal radiating fins 8, 8, the pipes being secured with their lower ends opening through the bottom plate 9 and their upper ends opening through a similar top plate, not shown. Thus the tubes form a through-connection from the lower

chamber 3, to the upper chamber 4. The radiator outlet 10, leading to the circulating pump and the water jacket, may be of the usual location and construction.

5 The radiator is shown as provided with a fitting which may be secured to the rear face thereof in any of the ways now employed for the usual hot water inlet fitting. The rearwardly presented portion 11 may be of the

10 same size and designed for attachment of the hose connection from the top of the water jacket in the same way as at present, but the rear end of the casting is blanked off, instead of opening through into the top of the radi-

15 ator. Two branch passages 12, 13, are preferably formed on easy curves so as to afford easy flow paths for the steam or water which, under certain conditions, will flow through the same at high speed. The branches 12,

20 13, will be of combined cross section sufficient to take care of the maximum flow of the cooling medium but preferably the flow section of the pipe 11 is even greater than this.

25 The pipe 11, branches 12, 13, and the base plate 14, are preferably an integral casting and the latter may be secured to the rear face of the radiator by bolts or rivets 15.

The two branch pipes 16, 17, are secured 30 steam-tight in the outlets of passages 12, 13, in any desired way as by screw-threading, brazing or otherwise. Preferably these branch pipes are close to the rear face of the radiator and extend horizontally to the re-

35 spective sides thereof, thence downward along the sides, as at 18, 19, entering the chamber in the bottom of the radiator as at 20, 21, respectively. Inside of the radiator they are preferably provided with outlet por-

40 tions 22, 23, shown as adapted to discharge toward each other.

Above these nozzles, and preferably at or 45 near the desired working level of the water, but a substantial distance below the bottom

50 9 of the core, is a baffle plate 24 provided with perforations 25. The number and size of the perforations is such as to minimize splashing of the water by side sway of the car or by violent boiling, also to distribute the steam more uniformly across the bottom of the core.

I claim:

55 1. A radiator having a lower chamber in which steam and water may be separated, and above the same, cooling passages into which the steam may rise, in combination with means for circulating boiling water or steam in said lower chamber including a plurality of spaced apart inlets; an outlet for the separated water and condensate, and a baffle plate extending across the chamber and promoting uniform distribution of rising steam.

60 2. A radiator having a lower chamber in which steam and water may be separated,

and above the same, cooling passages into which the steam may rise, in combination with means for circulating boiling water or steam in said lower chamber including a plurality of spaced apart inlets located on 70 opposite sides of the center of said chamber; an outlet for the separated water and condensate, and means baffling the flow of water and steam from the inlets to the cooling passages.

75 3. A radiator having a lower chamber in which steam and water may be separated, and above the same, cooling passages into which the steam may rise, in combination with means for circulating boiling water or 80 steam in said lower chamber including a plurality of spaced apart inlets located near opposite ends of said chamber and discharging towards each other; and an outlet for the separated water and condensate.

85 4. A variable-duty, air-cooled radiator for cooling systems of internal combustion engines, said radiator being provided below the honeycomb with a lower chamber, and means for circulating the water and steam medium from the engine through said chamber beneath the honeycomb, said means including a plurality of conduits terminating in oppositely directed nozzles discharging in said space, towards each other, and from opposite ends thereof, whereby the localizing of rising steam through a relatively small section of honeycomb is prevented.

90 5. A variable-duty, air-cooled radiator adapted for use with the cooling passages thereof below the level of the outlet from the water jacket of an internal combustion engine to be cooled thereby, and having a lower chamber from which steam may rise into said cooling passages, in combination with connections for leading the hot water or steam down to the level of the lower chamber, said connections including a fitting secured to the top of the radiator near the level of the water jacket outlet and having an intake which is rearwardly presented for communication with said outlet, and a pair of diverging branch passages from said intake including pipes extending in opposite directions along the top of the radiator, down the sides thereof and into the respective ends of the lower chamber beneath the cooling passages.

95 6. A variable-duty, air-cooled radiator of the upright type adapted for use on motor vehicles and the like with the upper part of the radiator located near the level of the outlet of the water jacket of the internal combustion engine which drives the vehicle, said radiator comprising a lower chamber, an upper chamber, and an intermediate core, and, in combination therewith, a conduit connection for the water jacket outlet, located adjacent the rear face of the upper chamber of the radiator, and branch pipes

from said conduit extending in opposite directions adjacent the rear face of the radiator, down the sides and into the lower chamber, together with a perforated baffle plate located above the discharge outlets of said branch pipes.

7. A variable-duty, air-cooled radiator of the upright type adapted for use on motor vehicles and the like with the upper part of 10 the radiator located near the level of the outlet of the water jacket of the internal combustion engine which drives the vehicle, said radiator comprising a lower chamber, an upper chamber, and an intermediate core, 15 and, in combination therewith, a conduit connection for the water jacket outlet, located adjacent the rear face of the upper chamber of the radiator, and branch pipes from said conduit extending in opposite directions adjacent the rear face of the radiator, down the sides and into the lower chamber, together with a perforated baffle plate located above the discharge outlets of said branch pipes, but substantially below the 20 level of the lower inlets of the cooling passages of the core.

8. A variable-duty, air-cooled radiator of the upright type adapted for use on motor

vehicles and the like with the upper part of the radiator located near the level of the 30 outlet of the water jacket of the internal combustion engine which drives the vehicle, said radiator comprising a lower chamber, an upper chamber, and an intermediate core, 35 and, in combination therewith, a conduit connection for the water jacket outlet, located adjacent the rear face of the upper chamber of the radiator, and branch pipes from said conduit extending in opposite directions adjacent the rear face of the radiator, down the sides and into the lower 40 chamber.

9. An up-flow condenser comprising a lower chamber and a radiating core or honeycomb above the same, means for discharging water and steam from the engine into said lower chamber and a perforated baffle plate arranged above the level of the 45 inlet for steam or water to promote uniform distribution of rising steam to the various 50 sections of the honeycomb.

Signed at New York in the county of New York and State of New York this sixteenth day of November, A. D. 1922.

SAMUEL W. RUSHMORE.
